UNITED STATES PATENT OFFICE.

RUSSELL PRATT, OF CHICAGO, ILLINOIS, ASSIGNOR TO THE CHICAGO DAILY NEWS, INC., A CORPORATION OF ILLINOIS.

DESIGN FOR A BADGE.

Application filed May 24, 1926. Serial No. 17,826. Term of patent 14 years.

To all whom it may concern:

Be it known that I, RUSSELL PRATT, a citizen of the United States, residing in Chicago, in the county of Cook and State of Illinois, have invented a new, original, and ornamental Design for Badges, of which the following is a specification, reference being had to the accompanying drawings, forming part thereof.

As shown in these drawings: Figure 1 is a front view; and Figure 2 is a cross sectional view taken on the line 2-2 of Figure 1.

I claim:

The ornamental design for a badge as shown.

RUSSELL PRATT.
